CLAIM

The ornamental design for a lawn mower engine cover, as shown and described.

DESCRIPTION

FIG. 1 is a perspective view of a lawn mower engine cover showing my new design;
FIG. 2 is a rear elevational view thereof;
FIG. 3 is a front elevational view thereof;
FIG. 4 is a left side elevational view thereof;
FIG. 5 is a right side elevational view thereof;
FIG. 6 is a top plan view; and,
FIG. 7 is a bottom plan view thereof.

The dashed line indicate a lawn mower for use therewith and form no part of the present invention.
